UNITED STATES PATENT OFFICE

ERICK G. WALLINDER, OF DULUTH, MINNESOTA

FOLDABLE TABLE

Application filed March 9, 1931. Serial No. 521,095.

This invention relates to folding tables and has special reference to such tables particularly adapted for use as banquet, picnic tables, or the like.

6 The principal object is to provide a more practical, simple, and staunch table of this character than heretofore known.

10 Other objects and advantages of the invention will appear in the following description thereof.

Referring now to the accompanying drawing, forming part of this application, and wherein like reference characters indicate like parts:

15 Figure 1 is a bottom plan view of one of the improved tables as it appears when folded; and

Figure 2 is a vertical section on the line 2—2 Figure 1, showing a fragmental portion of one pair of legs in open position; while

20 Figure 3 is an enlarged section similar to Figure 2, through the hinge, showing the legs in folded position.

25 1 represents the table top and 2 a depending marginal reinforcing member thereabouts. 3 represents a transverse bar at either end of the table, fixed to the under side of the top, and spaced from the end marginal member, and which bar varies in thickness in proportion to the width of the table. This bar acts also as a reinforcing member for the top and a support for the legs.

30 A small transverse bar 4 is also fixed to the under side of the table top intermediate of the marginal members which acts as a support for the metal strip 5—6 extending centrally of the table from the cross-bar 4 to the cross-bar 3, and to both of which it is attached as well as to the under side of the table top, as indicated at 6, the other portion 5 of the strip being spaced from the table top forming a channel 7 therebetween, which channel terminates adjacent the portion 6 in an inclined loop 8, the purpose of which will be described later.

To each bar 3 is pivotally attached adjacent the innermost edge thereof as by the hinges 9 a pair of legs indicated at 10. These legs may be of any desired construction, but the hinge arrangement is peculiar in that one half

of the hinge is positioned prone upon the under face of the bar 3 with the pivotal portion occurring over and above the lower innermost edge of the bar, while the other half of the hinge is brought down and fastened prone against the back side of the leg member and offset the thickness of the bar 3 on the end of the legs, so that when the pair of legs is in supporting position under the table, they occur approximately centrally beneath the innermost edge of the bar 3 with the adjacent end of each leg portion abutting against the horizontal portion of the hinge, thus insuring a positive limitation of motion outwardly of the leg member when swung into supporting position.

As a preferred form of pair of legs there is provided the two spaced transverse members 11 and 12, the latter being spaced downwardly from the end of the leg members proper, and the former still further downwardly towards the free ends of the legs, and in the two corners thus formed at the junction of the member 11 with the legs proper is placed a metal bracket 13 for pivotal support of the V-shaped brace 14, the bent termini of which extend through the depending half of the metal angle bracket, and the positioning of this pivotal point of the brace is such that when the pair of legs is in its ultimate supporting position for the table the apex of the bracket 14 will fall within the slot formed by the inclined loop 8 as clearly shown in Figure 2 of the drawing; this position being automatically assumed by the transverse action of the edge of the horizontal portion of the bracket 13 impinging against the portions of the brace 14 adjacent the pivotal connections of the brace. This is an essential feature of the invention to insure the automatic ultimate positioning of the brace when the pair of legs are adjusted to supporting position.

Now when it becomes desired to fold the legs the apex end of the brace must be stressed against the normal bias to such locked position until such end thereof becomes free to traverse the channel 7, when the legs may be readily folded into position prone against the under side of the table top,

as shown in Figure 1, when they are preferably wholly within the plane of the lower face of the marginal member 2 resulting in a neat, compact and conveniently assembled 5 folding table.

Having thus described my invention, what I claim and desire to secure by Letters Patent, is:

1. A brace for a pair of foldable table legs 10 comprising a V-shaped member the spaced termini of which are pivotally attached to the legs, a track longitudinally of the under side of the table top and having a notch therein and the apex of the brace slidably attached to 15 the track, and means whereby final placing of the legs into ultimate supporting position causes stress in the brace which forcibly urges the apex of said brace towards locked position in said notch.
- 20 2. The combination with a table top, of a transverse bar upon the under side of the top and inwardly from either end thereof, a pair of legs hingedly united to each bar and foldable inwardly therefrom and outwardly 25 thereagainst, and locking means for each pair of legs, said hinges being offset to overlap the end of the legs abutting the bar a distance equal to the thickness of the latter, thereby to substantially lie prone against the table 30 top when folded.
3. A table having legs foldable inwardly against the under side of the top thereof, tracks each having a notch therein secured to 35 said table top, V-shaped braces carried by said legs and operable in said track notches for holding the legs in extended position, and means carried by each pair of said legs for forcibly urging the brace toward said notch when the legs are extended.

40 In testimony whereof I affix my signature.

ERICK G. WALLINDER.
